UNITED STATES PATENT OFFICE

ROYAL B. LEE, OF SAN DIEGO, CALIFORNIA

PERPETUAL CALENDAR

Application filed November 16, 1929. Serial No. 407,761.

My invention relates to perpetual calendars, and the objects of my invention are: first, to provide a calendar of this class in which the proper weekly calendar for any month of any year marked thereon may be readily obtained with a minimum amount of manipulating; second, to provide a calendar of this class in which when once set, the only visible characters thereon pertain solely to the year, month and weekly calendar desired, all other characters being covered, thereby avoiding confusion; third, to provide a calendar of this class in which the setting of the desired year and month automatically indicates the particular weekly calendar to be used; fourth, to provide a calendar of this class in which all the possible weekly calendars are printed on a single card which is shiftable in register with a window, exposing only the desired portion of the calendar; fifth, to provide a calendar of this class in which calculation is eliminated or reduced to a minimum; sixth, to provide a calendar of this class which is particularly applicable for use as an advertising novelty; seventh, to provide a calendar of this class in which all moving parts are well protected from wear; and eighth, to provide on the whole, a novelly constructed perpetual calendar which is extremely simple of construction proportional to its functions, durable, efficient in its action, and which will not readily deteriorate or get out of order.

With these and other objects in view as will appear hereinafter, my invention consists of certain novel features of construction, combination and arrangement of parts and portions as will be hereinafter described in detail and particularly set forth in the appended claims, reference being had to the accompanying drawings and to the characters of reference thereon which form a part of this application, in which:

Figure 1 is a front elevational view of my perpetual calendar; Fig. 2 is a sectional view thereof through 2—2 of Fig. 1; Fig. 3 is an elevational view of the year-indicating disk; Fig. 4 is an elevational view of the month-indicating disk; and Fig. 5 is an enlarged,

fragmentary, sectional view through 5—5 of Fig. 1.

Similar characters of reference refer to similar parts and portions throughout the several views of the drawings.

Casing 1, year-indicating disk 2, knob 3, month-indicating disk 4, knob 5, segment member 6, knob 7, and transparent material 8 constitute the principal parts and portions of my perpetual calendar.

The calendar is enclosed by a casing 1, which comprises two rectangular-shaped front and back members separated from each other and arranged in parallel disposed planes by relatively thin edge walls. Mounted within the casing 1, adjacent the rear wall, and to one end, is a year-indicating disk 2, which is made as large as possible. The indicating disk 2 is supported relative to the front side of the casing 1 by the shank portion 3^a of a knob 3. The shank of the knob 3 is firmly secured to the disk so that it may be readily revolved.

Printed adjacent to the periphery of the disk 2 are a plurality of characters 2^a representing the various years for which the calendar is adapted to register. Only the last two characters of each year need be printed on the disk 2.

The forward side of the casing 1 is provided near its upper margin with an opening 1^a therein, which registers with the characters 2^a, but only registers with the characters for a single year at a time, as shown in Fig. 1. Adjacent this opening, at the left-hand side thereof, are printed the characters "19" which when read with the exposed characters 2^a complete the year date, such as the year "1929" shown in Fig. 1.

Between the characters 2^a and the hub of the disk 2 are provided a plurality of radially extending sets of numerical index characters 2^b. There are twelve of these characters in each set, corresponding to the twelve months of the year. These characters are adapted to be exposed by a rectangular opening 1^b formed in the front side of the casing 1. The opening 1^b preferably extends horizontally towards the further end of the casing from the knob 3. The characters 2^b are

arranged from "1 to 7", inclusive, and represent the calendar segments to be described hereinafter.

Offset horizontally from, and overlapping the disk 2, is a month-indicating disk 4, which is also annular and approximately the same size as the disk 2. The disk 4 is also supported relative to the front side of the casing 1 in a manner similar to the disk 2 by means of a knob 5. Printed adjacent to the periphery of the disk 4, as indicated by 4^a, are the words "January, February, March," etc., representing the twelve months of the year. Below each month name 4^a, are the words "30 days" or "31 days", as indicated by 4^b. For February, the characters read "28 days L. Y. 29".

The month names 4^a and the day-indicating characters 4^b therefor are adapted to fitting characters 2^b therefore are adapted to provided in the casing 1 vertically above the knob 5, and in approximately horizontally disposed relation to the opening 1^a.

The disk 4 is provided with a plurality of slots 4^c, one for each month of the year. The disk 4 overlaps the characters 2^b of the disk 2. The slots 4^c are so arranged that for each month name exposed in the opening 1^a, there will be a slot 4^c exposing just one character of the said index characters 2^b, which is registering with the opening 1^b, as shown in Fig. 1.

Thus, for November, only the character "6" is exposed, the others being closed by the opaque portion of the disk 4. For January, the slot 4^c is adjacent the left-hand end, and for December, the slot is opposite the right-hand end of the character sets 2^b. The openings 1^a and 1^b, being approximately ninety degrees from each other, the slot 4^c for January is on the same radius line as the month character of October, as shown in Fig. 4.

Mounted so as to overlap the disk 4, on the opposite side thereof from the disk 2, is a weekly calendar member 6. This member is in the form of a circular segment and is pivotally mounted relative to the front side of the casing 1 by means of a knob 7 positioned adjacent the lower end of the casing, as shown in Fig. 1.

Arranged near the upper end of the segment member 6 are six arcuately disposed lines of numerals divided into thirteen columns. The first line reads from "1 to 7", the second line from "2 to 14", the third line from "9 to 21", the fourth line from "16 to 28", the fifth line, "23 to 31", and the sixth line, "30 to 31". The numeral "1" in the first line begins the seventh column from the left, leaving six blank spaces in the first line. The numeral "31" of the fifth line ends in the fifth space from the right-hand side, leaving four empty spaces in this line. Only two characters "30 and 31" are in the last

or sixth line, leaving five spaces on the right-hand side of character "31".

Formed in the casing 1 is an arcuate opening 1^d adapted to expose all six of the lines, but only seven of the vertical columns. The segment member 6 is adapted to be shifted so that any seven of the columns and numerals thereon are exposed by the opening 1^d. Printed above the opening 1^d, so that they are opposite the seven columns of figures registering therewith, are characters representing, in a manner similar to the conventional weekly calendar, the various days of the week.

Below the opening 1^d, is a small opening 1^e adapted to expose a single character. Printed upon the segment member 6 so as to register one at a time with the opening 1^e are seven index characters, arranged from "1 to 7" inclusive. When the character "6" is opposite the opening 1^e, the numeral "1" is in the second exposed column from the right-hand side, indicating that that particular month begins on Friday. If the numeral 1 only in the upper line were exposed the segment member 6 would be at its extreme right-hand side.

The operation of my perpetual calendar is as follows:

The disk 2 is rotated until the characters representing the desired year are exposed by the opening 1^a. The disk 4 is then rotated until the desired month is exposed in the opening 1^b. This exposes one index character of one of the character sets 2^b. The character exposed indicates the character that should be exposed by the opening 1^c in order to have the proper calendar in register for the desired year and month.

As shown in Fig. 1, the year "1929" and the month "November" is exposed, and the numeral "6" is exposed by the slots 1^b and 4^c. The weekly calendar segment 6 is positioned so that the numeral "6" is exposed by the opening 1^c, thereby causing a portion of the characters 6^a on the segment 6 to register with the opening 1^d and form a complete weekly calendar for the month of November.

By merely rotating the disks back or forth to the desired month and year, a single number is exposed by the slots 1^b and 4^c, and then by setting the segment 6 so as to correspond to this number, the proper weekly calendar is readily set.

The leap year can readily be indicated by coloring the background of the numerals 1^a corresponding to the leap year date, or by coloring the background of the numeral sets 2^b corresponding to the leap year, or both, as indicated by the crosshatched lines 2^c representing colors. If desired, however, the numerals themselves may be printed in contrasting colors rather than tinting the background.

The various openings 1^a, 1^b, 1^c and 1^d are

covered by a thin sheet of transparent material, such as celluloid 8, as shown in Figs. 2 and 5.

It is obvious from the construction as illustrated in the drawings and described in the foregoing specification that there is provided a perpetual calendar as aimed at and set forth in the objects of the invention, and though I have shown and described a particular construction, combination and arrangement of parts and portions, I do not wish to be limited to this particular construction, combination and arrangement, but desire to include in the scope of my invention the construction, combination and arrangement substantially as set forth in the appended claims.

Having thus described my invention, what I claim as new and desire to secure by Letters Patent is:

20 1. In a perpetual calendar, a casing, a rotatable disk mounted therein, said disk provided with characters representing the years and sets of index characters corresponding to said years, a second disk provided with characters representing months, and a slot for each month arranged to uncover a certain index character, said casing provided with openings therein adapted to expose at one time, characters representing a single year date, characters representing a single month of a year, and an index character exposed by the slot in said second disk, and a weekly calendar member arranged to be set according to the said exposed index character.

35 2. In a perpetual calendar, a casing, a rotatable disk mounted therein, said disk provided with characters representing the years, and sets of index characters corresponding to said years, said casing provided with openings therein arranged to expose a certain year date and a corresponding set of index characters, a second disk rotatably mounted within said casing, said second disk provided with words indicative of the various months of the year, an opening in said casing for exposing words indicative of a certain month, said second disk arranged to conceal all but one of the index characters exposed by the second mentioned opening in said casing, and 50 a weekly calendar mounted in said casing arranged to be shifted so as to expose a weekly calendar corresponding to the index character revealed by said second disk.

3. In a perpetual calendar, a casing, a rotatable disk mounted therein, said disk provided with characters representing certain years and sets of index characters corresponding to the various months of said years, said casing provided with a first opening exposing a certain year date, and a second opening exposing a single set of index characters, a second disk mounted in said casing and extending into overlapping relation with said first disk between said set of characters exposed by said second opening, said second

disk provided with the names of the various months of the year printed thereon, said casing provided with a third opening exposing one month name at a time, said second disk provided with a plurality of slots, one slot corresponding to each month arranged to co-act with said second opening and expose a single one of said set of characters, and a shiftable weekly calendar arranged to be set so as to correspond to the index character exposed by said second opening and a slot in said disk.

4. In a perpetual calendar, a casing provided with a plurality of openings in its forward side, a pair of disks rotatably mounted therein, the one disk having printed thereon year dates and sets of index characters corresponding to said year dates, the other of said disks having the months of the year printed thereon and slots cut therein corresponding to each month of the year, each of said slots arranged to expose a certain character of any set of characters on said first disk, and a composite weekly calendar member having printed thereon the various arrangements of days in a month, and index characters corresponding to the index characters on said first disk, said openings in said casing arranged to expose at one time a single year date, a single month name, a single index character on said first disk, a corresponding index character on said weekly calendar member, and a certain section of said calendar corresponding to the year and month exposed.

5. In a perpetual calendar, a pair of disks, the one having year dates formed thereon and the other having the months of a year formed thereon, index means, said disks arranged to co-act so as to reveal said index means, and a composite weekly calendar means arranged to be set according to said index means so as to reveal the proper weekly calendar for a given year date and month.

6. In a perpetual calendar, a pair of disks, the one having year dates formed thereon and the other having the months of a year formed thereon, index means, said disks arranged to co-act so as to reveal said index means, a composite weekly calendar means arranged to be set according to said index means so as to reveal the proper weekly calendar for a given year date and month, and a casing for said disks, and means having openings therein arranged to expose only a given year date, a given month date, and the proper index means and the proper weekly calendar for said year and month dates.

In testimony whereof, I have hereunto set my hand at San Diego, California, this 7th day of November, 1929.

ROYAL B. LEE.
